DESIGN FOR A SURF MATTRESS

Reginald M. Banks and Dorothy A. Banks,
Woodmere, N. Y.

Application August 5, 1938, Serial No. 79,123

Term of patent 7 years

To all whom it may concern:

Be it known that we, Reginald M. Banks and Dorothy A. Banks, both citizens of the United States both residing at Woodmere, in the county of Nassau and State of New York, have invented a new, original, and ornamental Design for a Surf Mattress, of which the following is a specification, reference being had to the accompanying drawing, forming part thereof wherein:

Figure 1 is a side elevational view of a surf-mattress, showing our new design, the opposite side being the same as the side illustrated; and

We claim:

The ornamental design for a surf mattress, substantially as shown and described.

REGINALD M. BANKS.

DOROTHY A. BANKS,
